(57) **CLAIM**

The ornamental design for a pedestal, as shown and described.

DESCRIPTION

FIG. 1 is a perspective view of a pedestal showing my new design;

FIG. 2 is a first side elevational view thereof;

FIG. 3 is a second side elevational view thereof;

FIG. 4 is a perspective view of a second embodiment of a pedestal showing my new design with a shorter/wider base;

FIG. 5 is a first side elevational view thereof; and,

FIG. 6 is a second side elevational view thereof.

The views of the pedestal not shown form no part of the claimed design. The broken lines depicting the table top represent environmental elements only and form no part of the claimed design.
